UNITED STATES PATENT OFFICE.

ROBERT W. SCOTT, OF BOSTON, MASSACHUSETTS, ASSIGNOR, BY MESNE ASSIGNMENTS,
TO SCOTT & WILLIAMS, INCORPORATED, A CORPORATION OF MASSACHUSETTS.

STARTING SELVAGE AND TUCKING DEVICE FOR KNITTING-MACHINES.

1,348,144.

Specification of Letters Patent. Patented July 27, 1920.

Application filed July 24, 1914. Serial No. 352,897.

To all whom it may concern:

Be it known that I, ROBERT W. SCOTT, a citizen of the United States, and resident of Boston, in the county of Suffolk and

5 State of Massachusetts, have invented certain new and useful Improvements in Starting Selvage and Tucking Devices for Knitting-Machines, of which the following is a specification.

10 My invention relates to improvements on an existing type of knitting machine to enable the machine to begin a new section of fabric automatically upon needles bare of previous fabric, and to enable the production 15 at any desired time in the operation of tuck stitches, for instance to form a stop course to prevent raveling of the fabric in the direction in which it was knit.

In the accompanying drawings:

20 Fig. 1 is a left side elevation, partly broken away, of a sufficient part of a knitting machine to show one illustrative instance of the application of my new devices.

25 Fig. 2 is a front elevation.

Fig. 3 is a detail section showing the needles and web-holders;

Fig. 4 is a detail top view of the leading stitch cam;

30 Fig. 5 is a detail showing two kinds of needles employed;

Fig. 6 is a development of the cam cylinder showing the path of the needles in two different positions of the cam;

35 Figs. 7, 8 and 9 are diagrams illustrating the relation of the needles to the yarns at the starting courses;

Figs. 10, 11 and 12 are diagram plans of the needles illustrating another operation 40 for beginning fabric;

Figs. 13 and 14 are diagram elevations of web-holders and needles.

The invention, which is applicable to independent needle machines of any existing 45 type, is shown in the drawings for one illustrative embodiment only as applied to a machine of the type shown in Letters Patent to J. D. Hemphill, No. 933,443, September 7, 1909, and in which the needle cylinder 50 is mounted for rotary or reciprocatory movements with respect to relatively stationary stitch cams 8, 9, 10, 11 on a cam-

carrier 4 movable radially in a gap having cam faces 7 in a cam ring 6, which cam ring is stationary except for movements of 55 adjustment to alter the stitch length; said ring terminating in a ledge at the top at the level of which independently movable latch needles travel at a height insufficient to advance the ends of the latches through 60 the loops held on the shanks of the needles at a level determined by web-holders 20 carried in a bed attached to the needle cylinder.

I provide the machine with devices to 65 secure the taking of the yarn of a first course (which may in part or throughout be formed of overlapped or multiple yarns from two or more successive feedings) in such a manner that alternate or recurrent 70 needles of the series of needles pass upwardly in front of said first course, as a step in the production of a beginning selvage of the genus shown, described and claimed in my Letters Patent No. 1,045,621, 75 November 26, 1912. Such a selvage is fast against raveling in the direction in which it is knit and moreover provides an efficient aid to the needles in the machine to cause them all to begin knitting when desired 80 with regularity. The new devices also provide for the operation of recurrent needles to make tuck stitches for any desired purpose, for instance to make at a later time in the production of the fabric a stop course 85 to prevent raveling or running of ladders caused by rupture thereof after it is complete, which stop course may be of the type shown in Fig. 3 of the patent of L. A. Costello, No. 976,555, dated November 11, 1910. 90

Referring now to Fig. 1, the machine improved comprises a pattern or cam shaft *s'* upon the end of which I mount a supplemental drum 30, Figs. 1 and 2, for contact with the lower end of a lever 31 pivoted on 95 a shouldered stud 32 held on the frame of the machine by a lock nut 33. The upper end of the lever 31 extends above the bed plate *A* at the top of the machine and is provided with a bore hole in which an adjustable pin 34 is made fast by a set screw 35.

Fast on the bed-plate of the machine is a standard 36 upon which is pivoted at 37

a rocker 38 having one face for contact with the pin 34 and another face resting normally against stitch cam 8 in the diagonal plane of said stitch cam.

- 5 Said stitch cam, Fig. 4, instead of being rigidly mounted upon the carrier block 4 sliding radially toward and away from the needle cylinder, as in the machine improved, is pivoted on a stud 40, carried by said block, to move in said diagonal plane, said stud being surrounded by a spring 41 tending to move the cam 8 down and to the right as viewed in Figs. 1 and 6. Said cam 8 is slotted at 42 for a shouldered hold-down screw, and as usual is provided with an opening 44 through which the picker axis 45 freely extends.

Fast on the top of the top center cam 10 I provide a bent stop piece 50 carrying a limit screw 51 and jam nut 52, in a position to contact with the upper end of the cam 8 and limit its upper swing.

The arrangement is such that when the cam-carrier is in operative position the rocker 38 transmits to the cam 8 impulses received from the lever 31 and pin 34, to swing the stitch cam 8 about the stud 40 to take it to and hold it in the upper position permitted by the screw 51, in which position said cam is adjusted for knitting on the back or reciprocal stroke, and for clearing all the needles encountering its upper face in the direction for rotary work; or to permit said cam under the influence of spring 41 to drop against the incline 7 of the cam ring 6 to lower the cam to prevent needles approaching in the direction for rotary work at the level of the ledge at the top of the cam ring 6 from being advanced 40 as far as usual.

I provide the machine with the usual series of long and short butt needles for the usual stocking knitting purposes.

In order to coöperate with my improved devices recurrent needles of the series are provided with latches x shorter than those of the remaining needles, so that the entire series of needles whether the long or short butts, will present an alternation of single 45 needles or groups of a plurality of needles differing from each other in the lengths of their latches.

Referring now to Fig. 5, and assuming an alternation of needles with shorter latches x and needles with longer latches y , when the needle carrier is moving in the direction for rotary work and when the cam 8 is in its lower position needles with short latches x will clear the said latches through their 50 loops at the usual knocking-over instruments 20 of the machine, while the needles with the long latches y will not be advanced far enough to clear their loops at the stitch cam, and will accumulate loops of yarn at each 65 passage of the stitch cams.

I provide on the drum 30 a depression 55 in such a position with respect to cams f^2 , f^4 on the drum f , on shaft s' , Fig. 2, for controlling the yarn guide levers d' , so as to cause the cam 8 to take its lower position in a 70 predetermined relation to the feeding of an initial yarn to begin an article.

In the machine improved the shaft s' is driven by a ratchet motion enabling the said shaft s' to advance during substantially one 75 and one-half revolutions of the needle carrier.

The depression 55 of the supplemental pattern drum 30 may be at a position to co-operate with the lever 31 immediately after 80 the beginning of an article to be knit, the lever 31 resting, at the beginning of the article, with its lower end against the periphery of the drum 30, as shown in Fig. 1. The stitch cam 8 is then in its normal position and 85 all of the needles are elevated through their normal distance, and depressed at the following stitch cam 11.

At the beginning of the article one of the said cams f^2 , f^4 shown as cam f^4 , drops one 90 of the yarn guides d' into its operative position to feed yarn to the hooks of all the needles during at least one revolution of the needle carrier. Certain of the needles may receive this yarn a second time, as illustrated in Fig. 7, but the yarn first taken will not knit with respect to the yarn when taken the second time, there being nothing to hold the first taken yarn against the needles to close the latches when they are depressed 95 by cam 11. Having fed all the needles with the yarn of course 1, (Fig. 7) the yarn guide lever is now elevated to cease feeding any yarn, cam f^4 running from under indicator lever f^3 , whereupon the depression 55 becomes active to drop the stitch cam 8 to the position shown in Fig. 6, in which position the long latch needles will not be elevated to clear their latches above the yarn previously taken for course 1. Said yarn rotates idly with the needles, between which it passes at the point where it left them upon the elevation of the yarn guide d' , as at g , Fig. 7.

The effect of idle revolutions of the machine in the absence of all yarns except that already fed, when the stitch cam 8 is in the lowered position, is to cause the shorter latch needles with respect to the yarn of course 1 first to clear their latches x over said yarn 120 and then to cast off the bights h first taken, while retaining the bights k at each of the long latch needles, which have not advanced to clear their latches y , as shown in Fig. 8.

This result will not be accomplished safely, 125 however, if the web-holders 20 are permitted to recede with respect to the retracting needles in their ordinary movement for knitting. I therefore arrange the pattern devices of the machine, which already com-

prises a device *m* connected to a lever *f*⁶ and cam *f*⁷ on drum *f*, for moving the web-holder cam 21 inward during said idle revolutions to maintain the web-holders in an inner position to hold the yarn of course 1 against the faces of the needles to insure closure of the latches *x* and to insure passing the loops or bights cast off by the short latch needles inwardly behind said needles at their subsequent advance at the following slope 7.

By the described operations I have provided the needles with a run of yarn (which may be double in part) held in the hooks of the long latch needles and held behind the position of the short latch needles, as shown in Fig. 8. The machine may operate idly for as many revolutions as desired with the yarn in this position. The existing devices for moving the shaft *s'* will now rotate the drum 30 to cause the described connection to elevate the leading stitch cam to clear all the needles and simultaneously therewith or prior thereto another or the same yarn guide *d'* carrying the desired yarn for the top of the leg of the stocking will be placed in an operative position by the connections from cams *f*² or *f*⁴, and the device *m* will be moved to render the web-holders 20 operative. The second course 2 taken under these circumstances comprises the loops *w*, Fig. 9, lying on each side of the yarn of course 1, and subsequent knitting will be initiated with respect to said loops, the structure of the first three courses forming a fast selvage or edge of the genus described and claimed in my said Letters Patent 1,045,621. The yarn introduced for the second or later course may be a different yarn from the yarn of the first course, or the same yarn. The point of introduction of the yarn of the second course may coincide with the position of the first long latch needle sufficiently elevated to clear its latch, but I prefer to move the supplemental drum 30 and the main pattern drum *f* in such a manner as to drop in the yarn guide and operatively position the leading stitch cam at the same time, and therefore to feed yarn to a few needles comprising long latch needles not yet advanced to clear the starting course. The described movement of the web-holder cam occurring at the same or an earlier time, to its operative position will not have endangered the retention of the yarn of the starting course 1, if prior to the feeding of new yarn, because of the position of alternate bights of said course behind alternate needles, or groups of needles, as described.

I may if desired form the selvage and begin knitting upon the bare needles, utilizing as before a tucking operation, without the device of suspending the feeding of yarn during one or more courses. The existing machine is provided with web-holders 20 having slopes 20^a upon their upper edges,

the arrangement of said machine being such that when the web-holder cam 21 is in an inner position yarns taken by the needles will be brought down against said slopes 20^a and into the hooks of the web-holders, 70 by the draft of the needle, the web-holders being stationary.

Referring now to Fig. 10 the initial yarn 1 is fed during normal advance and retraction of the web-holders, or during their occupation of their advanced position, the result in either case being illustrated in Fig. 10, which is a plan showing slopes 20^a and the needles, the yarn 1 entering the hooks of all the needles and being taken into the 80 hooks of all the web holders. Course 2 is now fed to the needles, the web-holders being in their advanced position, and the advance of the needles being limited to fail to clear the long latch needles. The result is 85 illustrated in Fig. 11 from which it will be understood that the loop of yarn 1 may be knit off from all of the needles bearing the short latch *x*, while the long latch needles retain their original loop of course 1 and an 90 additional loop of course 2. On the next course tucking on the long latch needles ceases and all of the needles advance to take 95 yarn and knit with respect to their previous yarns, and the web-holders are given a normal movement.

Fig. 12 illustrates two courses 3 and 4 of normal fabric so made.

By the operations just described it will be seen that yarn 1 has been passed recurrently 100 back of and in front of the needles so that the normally knit yarn of course 3 surrounds the yarn of course 1 to form the selvage structure of my said patent. Course 2 is cast off at all the needles when the needles 105 are worked for course 3 forming no permanent structural part of the fabric, as shown in Fig. 12.

Figs. 13 and 14 illustrate the relation of short and long latch needles respectively 110 to their web-holders when said needles are advanced to take course 2.

In either of the above procedures for forming beginning selvages by a tucking operation it is desirable to feed the initial 115 course or courses to needles making a movement which, if they were knitting would produce a short stitch, to provide as little yarn as possible for said initial course or courses.

In machines of the type selected for illustration, as fully specified in the patent above mentioned, the length of stitch is automatically adjusted by raising and lowering the cam-carrier 4 in respect to the remainder of 125 the machine to shorten or lengthen the stitch.

It will be understood without illustration, that when the machine is intended to automatically knit one article and then begin to 130

knit another after an idle revolution, that I may provide it with any known or usual form of mechanical latch opener to open the latches of the bare needles prior to feeding the initial course, such for instance as the latch opener described and claimed in my application Serial No. 845,845 filed June 18, 1914.

My new devices provide for automatically 10 beginning knitting by a selvage on the bare needles without the use of independently movable jacks or jack cams or other devices in use for that purpose at present.

The movable advancing cam constituted 15 by the upper surface of the cam 8 in my new device is available for tucking for any desired purpose upon the needles having longer latches y. A single line or row of tuck stitches extending around the fabric 20 is, as explained and shown in Fig. 3 in the patent to Costello above, a serviceable structure for preventing the running of dropped stitches resulting from a break in the fabric, and I may cause the above described devices 25 to be operated at any desired point or points during the production of the article to produce such a row of tuck stitches, in which loops may be accumulated on the long latch needles during such an interval of knitting 30 on the other needles as may be desired. The loops are withheld on the long latch needles during the knitting of one intervening course, by retaining cam 8 in its lower position during one revolution of the knitting 35 head at least. Means for securing this movement of the cam 8 may comprise a recess as at 61 in the supplemental drum 30 at the desired point to cause the lower end of the lever 31 to enter said recess at a predetermined point in the passage of the needles 40 past the cam 8, and to move said lever 31 out of said recess at the next or a succeeding revolution, at or near the same point.

In the machine improved in order to 45 adapt it for transfer of fabric on to the needles, the sliding block carrying the stitch cams 8, 9, 10 and 11 is movable by hand radially away from the needle cylinder. If the machine is desired to be used for this 50 purpose, to maintain pressure by the lever 31 against the stitch cam 8 will render the movement difficult, and machines intended for this purpose may be provided with a supplemental drum 30 having a depression 55 62 to be brought opposite the lower end of the lever 31 when the machine stops at the completion of the previous article to relieve the pressure on the cam 8.

It will be evident that the described mechanism 60 comprising drum 30 and lever 31, and the rocker 38 for altering the position of the leading stitch cam is an effective device for coöoperating with needles differentiated by the lengths of their latches or otherwise for 65 any purpose, such as making fabrics tucked

or otherwise ornamented by variations of the stitch knit by one kind of needle.

What I claim is:

1. A knitting machine having in combination needles and means for forming a starting selvage comprising means to lay yarn in the hooks of all the needles, means to cast off said yarn unknit from recurrent needles only distributed among the remainder, and means for thereafter feeding yarn 75 to and knitting at said recurrent needles and needles intervening between them.

2. A knitting machine having in combination needles, means to lay an initial yarn in the hooks of all of the needles, means acting to cast said yarn unknit off of recurrent needles, and means thereafter acting to feed yarn to and knit at all of said needles, whereby said initial yarn is enveloped by 80 said first knit course to form a starting selvage.

3. In a knitting machine, needles and 85 yarn feeding devices, and means for operating the needles to knit in combination with means for causing cessation of yarn feeding 90 during operation of some of the needles only to cast off their loops.

4. In a knitting machine, needles and 95 yarn feeding devices, web-holders, and means for advancing and retracting said web-holders, in combination with means for rendering the retracting means for said web-holders inoperative during the operation of some of the needles to cast off their loops.

5. In a knitting machine, needles, and 100 means for beginning to knit comprising means for feeding yarn to all of the needles and means for casting said yarn from the hooks of recurrent needles, said casting-off means so operating as to retain the yarn in 105 the hooks of other needles and means for advancing said recurrent needles in front of their cast-off bights, said means being adapted to act prior to normal knitting.

6. In a knitting machine, needles and 110 means for forming a beginning selvage comprising means to lay yarn in the hooks of all the needles, and means for operating said needles in the absence of new yarn selectively to cast off said yarn from recurrent needles only distributed among the remainder, prior to normal knitting at all of said needles.

7. In a knitting machine, needles and 115 yarn feeding devices, web-holders and means to operate said needles in the absence of new yarn and in the association with web-holders held in an advanced position to selectively cast off the loops of recurrent needles only and advance said needles in front of 120 their cast-off bights prior to normal knitting.

8. In a knitting machine, means acting 125 at the beginning of knitting to form a beginning selvage comprising independent 130

- latch needles, means to feed an initial yarn to the said needles, means for clearing the bights of said yarn beneath the latches of recurrent needles only, and means operating 5 to hold the cast-off bights behind said recurrent needles, whereby upon further operation said recurrent needles pass in front of the yarn of said initial course.
9. In a knitting machine, series of needles 10 requiring to be advanced before casting off, yarn feeding devices, and means to render said devices operative at the beginning of knitting with respect to all of said needles, in combination with means for thereafter 15 rendering said feeding devices inoperative, and means acting to advance and cast off on one series of said needles while said devices are inoperative.
10. In a knitting machine, series of needles 20 requiring to be advanced different distances for clearing, yarn feeding devices, and means to render said devices operative at the beginning of knitting, in combination with means for thereafter rendering said 25 feeding devices inoperative, and means for advancing said needles through a distance sufficient to clear one series only while said devices are inoperative.
11. In a knitting machine, leading and 30 following stitch cams, a series of needles having latches intercalated among a series of needles having shorter latches, yarn feeding devices, and means to render said devices operative for initiating knitting, in combination with means for thereafter rendering said devices inoperative, and means for moving the leading stitch cam to change the effective height of one of its surfaces to clear the shorter latch needles only while 35 said devices are inoperative.
- 40 12. In a knitting machine the combination with means for feeding yarn and means for rendering said devices inoperative, of independent needles having long and short latches, stitch cams for rotary and reciprocatory work, each stitch cam comprising an advancing surface for elevating the needles to clear their loops below their latches, and means for positioning one of said stitch cams at a low point to clear the short latch needles only during cessation of yarn feeding.
- 45 13. In a knitting machine, means for forming a beginning selvage comprising independent needles, means to feed an initial course or courses of yarn to the said needles, and means to operate said needles in the absence of new yarn to clear the bights of said yarn beneath the latches and cast off said bights at recurrent needles only, whereby upon normal operation said recurrent needles pass in front of the yarn of said 50 initial course, and means acting thereafter to normally operate said needles in the presence of knitting yarn to knit another and 55 following courses.
14. In a knitting machine, independent needles, yarn feeding devices, means to actuate said yarn feeding devices to feed an initial yarn to the said needles, means to cause cessation of yarn feeding, and means 70 to cast off the bights of said yarn at recurrent needles only, in combination with means for thereafter normally operating said yarn feeding devices and said needles, whereby upon said normal operation said recurrent needles pass in front of the yarn of said 75 initial course, and other needles pass behind said initial course to take yarn and form a subsequent course drawn recurrently to opposite sides of said initial course. 80
15. In a knitting machine, yarn feeding devices and means to cause said devices to cease feeding yarn, in combination with series of latch needles requiring to be advanced different distances for clearing their 85 latches, a cam for advancing the needles, a mounting therefor permitting said cam to be lowered, and means for lowering said cam to prevent clearing of one series of said needles during operation of the machine 90 and during cessation of yarn feeding, and means for operating said cam at a predetermined time thereafter while feeding yarn to form tuck stitches. 95
16. In a knitting machine, yarn feeding devices and means to cause said devices to cease feeding yarn, in combination with series of latch needles requiring to be advanced different distances for clearing their latches, a cam for advancing the needles, a 100 mounting therefor permitting said cam to be lowered, and means for lowering said cam to prevent clearing of one series of said needles during operation of the machine and during cessation of yarn feeding. 105
17. The combination in a knitting machine of latch needles, and a cam carrier movable into and out of operative position, with a stitch cam and a needle cam for clearing the needle-latches mounted on said cam carrier, said clearing cam being movable on said cam-carrier to a plurality of adjusted positions while in contact with said needles, and means for moving said cam adapted for operation when said cam carrier is operatively positioned. 110
18. The combination in a knitting machine of latch needles and a cam-carrier movable into and out of operative position, with a needle-cam adapted to lift the needles 115 to clear their latches movable on said cam-carrier to a plurality of adjusted positions while in contact with said needles, and means for contact with said cam to move it when said cam-carrier is in an operative 120 position.
19. The combination in a knitting machine of needles, a stitch cam carrier block having a diagonal face, a needle-cam pivoted for movement on said face, whereby to vary 125 130

- the extent to which said cam moves the needles, a stop determining the position of said cam, and pattern controlled devices for normally holding said cam against said 5 stop.
20. In a knitting machine, needles and a needle cam group comprising a stitch cam having an upper advancing surface and a lower retracting surface, beneath which is a 10 normally free groove for needle butts, in combination with means for moving said cam through the width of said groove at predetermined times, to lower its advancing surface for a special movement of the 15 needles.
21. In an automatic knitting machine, needles and a stitch-cam pivoted to move from a normal operative position to another operative position, means tending to 20 rotate said cam on its pivot out of its normal position, and pattern controlled means for holding said cam in its normal position, and for permitting movement to its other position at predetermined times.
22. In a circular knitting machine, a stitch cam and a mounting therefor having a 25 diagonal face lying in the direction of one of the working faces of the cam, the cam being a part having a needle-advancing and a 30 needle-retracting surface on its inner end, and being pivoted at a distance from its inner end to move on the diagonal face of its mounting, in combination with means for automatically moving the cam about said 35 pivot to change its effect on the needles.
23. In a stitch-cam device for knitting machines, the combination of a needle-carrier, a block having a diagonal face movable away from said carrier to an inoperative position, a needle cam pivoted to move on 40 said face, and adjusting means for said cam movable in a plane at an angle to the direction of motion of said block, for contact with said cam when said block is operatively positioned. 45
24. The combination in a knitting machine of a needle cam pivoted to move in a diagonal plane, a standard, a rocker pivoted on said standard having one face in the plane of said cam, a vertical lever having at 50 one end a member movable therewith in a substantially horizontal plane for contact with the other face of said rocker, and pattern devices for operating said lever.
25. A knitting machine have in combination a stitch cam carrier vertically adjustable to change the length of stitch, a needle cam pivoted to move in a diagonal plane on said cam carrier, a rocker mounted to take 55 against said cam in any vertical position of said cam carrier, pattern mechanism, and a connection thereto mounted on a fixed part of the machine for operative contact with said rocker.
- In testimony whereof I have signed my 60 name to this specification in the presence of two subscribing witnesses.
